G. SMITH

WIRE FENCE STRETCHER

Filed July 6, 1921

Inventor
Grant Smith

By *Lancaster Ad Allevine*
Attorney

UNITED STATES PATENT OFFICE.

GRANT SMITH, OF BLUEFIELD, WEST VIRGINIA; MARGARET R. SMITH ADMINISTRATRIX OF GRANT SMITH, DECEASED.

WIRE-FENCE STRETCHER.

Application filed July 6, 1921. Serial No. 482,744.

To all whom it may concern:

Be it known that I, GRANT SMITH, a citizen of the United States, residing at Bluefield, in the county of Mercer and State of West Virginia, have invented certain new and useful Improvements in Wire-Fence Stretchers, of which the following is a specification.

This invention relates to a portable wire fence stretcher.

The primary object of the invention is the provision of a wire stretching apparatus, so conveniently mounted and easy of operation, as to permit the efficient stretching of a wire fence by a single individual.

A further object of the invention is the provision of a wire stretching device of the above described character, which specifically embodies an elongated frame, portably mounted, and including novel wire stretching apparatus.

Other objects and advantages will be apparent during the course of the following detailed description.

In the accompanying drawing, forming a part of this specification, and in which similar reference characters designate corresponding parts throughout the several views.

Figure 1 is a side elevation of the improved wire stretching device in operation for stretching a woven wire fence.

Figure 2 is a plan view of the wire stretching device in operation.

Figure 3 is a transverse cross sectional view taken on the line 3—3 of Figure 2.

Figure 4 is an enlarged fragmentary side elevation of certain details of the wire stretching apparatus.

In the drawings, wherein for the purpose of illustration is shown the preferred embodiment of my invention, the letter A designates the improved wire stretching device, comprising a frame B, and wire stretching apparatus C mounted thereon.

The improved wire stretching device A is preferably used in connection with a fence post D, and a clamp E affixed to a section of the wire mesh F, as will be specifically set forth.

The frame B, preferably includes a pair of longitudinal side members 10 and 11, converging toward an end, at which point the extreme ends of the members 10 and 11 are

rigidly connected by a bar 12, extending over the extreme ends of the members 10 and 11. A bar 13 preferably connects the rear end of the side members 10 and 11, said bar 13 being greater in length than the bar 12 to form the convergence of the members 10 and 11. Intermediate bars 14 may be conveniently positioned parallel to the bars 12 and 13, as desired. In order to sufficiently brace the frame structure B, a pair of longitudinal bars 15 and 16 are provided for parallel disposition between the side members 10 and 11; the same being affixed to the end bars 12 and 13, and the intermediate bars 14 in any preferred manner.

A wheel 17 having an axle 18 rigid therewith is mounted upon the longitudinal center of the frame B, as by the ends of the axle 18 engaging in suitable bearing straps 20, beneath the side members 10 and 11. It is preferred that the wheel 17 be relatively large in diameter, and located at the front end of the frame B, in such manner that the outer periphery of said wheel is spaced within the frame B, and adjacent the bar 12. Supporting members substantially V-shaped in formation are affixed to the rear of the frame B in vertical position, and immediately below the longitudinal members 10 and 11. Each of the members 21 and 22 has a vertical leg 23 extending downwardly immediately below the transverse brace or bar 13, and an inclined leg 24 connected to the lower end of leg 23 and inclined upwardly and away from said leg 23 for attachment to the bar 14.

A stay rod 25 is slidably attached by means of a strap 26 to the vertical leg 23 of the supporting member 22, and preferably upon the outside edge of said supporting leg 23. The stay rod 25 is provided with an upper outwardly hooked end 27, adapted for normal disposition over the longitudinal member 11, as shown by the dotted lines in Figure 3 of the drawings. When in this position, a pointed end 28 of the stay rod 25 is held suspended above the ground surface over which the improved wire stretching device A is positioned.

However, as before stated, the stay rod 25 is capable of turning and sliding within the strap 26, in such manner that said stay rod 25 may be driven down into engagement in the ground surface for attachment of the

rear end of the wire stretching device, and which will be more specifically set forth hereinafter.

A bracing bar 30 is pivotally and slidably mounted upon a rod 31, which rod is transversely mounted in the longitudinal members 10 and 11 parallel with the bracing bars 12, 13, and 14. The brace bar 30 is of sufficient length to project forwardly of the bar 12 when the same is resting upon the frame B. However, in operation, the brace bar 30 will be arranged upwardly at an acute angle with respect to the side members 10 and 11, as illustrated in Figure 1 of the drawings, and the forward end 32 of the bar 30 is necessarily cut at a bevel.

Regarding the wire stretching apparatus C, a drum 35 adapted to receive a cable 36 is rotatably mounted upon a rod 37, extending transversely of the frame B, and engaging in the members 10 and 11. It is preferred that the drum 35 be disposed between the intermediate longitudinal braces 15 and 16. Cable hooks 38 and 39 are likewise pivotally mounted upon the bar 37, and upon opposite sides of the cable 36, said hooks 38 and 39, however, lying in the frame structure B. A hand operated lever 40 is preferably pivotally mounted upon an extending end of the drum 35, and provided with a ratchet tooth 41, adapted for engagement with the teeth 42 upon the wheel 43; which wheel is preferably formed integral with the drum structure 35. In connection with the wire stretching apparatus C, a dog 45 is pivotally mounted upon the top of an intermediate brace bar 14, and adapted to ride over the teeth 42 of the wheel 43, as the wheel 43 is rotated by the operating lever 40.

In operation, the wire fence clamp E is attached to the reticulate fence F in accordance with standard practice. It is preferred that the clamp E in this instance, be of that type specifically described in my copending application Serial #482,743 filed July 6, 1921. The wire stretching device A is then transported over the ground surface by the operator grasping the handles 47, and moving the same in wheelbarrow fashion, until the forward bar 12 engages a side 48 of the post D, and opposite that side of the post facing the clamp E. The frame B is then placed in longitudinal alignment with the direction of the fence F, substantially as illustrated in Figure 1. The stay rod 25 is next driven into the ground as hereinbefore described, thus bracing the rear of the frame B against swinging movement incident to stretching of fence F. The brace rod 30 is next pivotally and slidably positioned on the cross rod 31, until the same can be lowered for engagement against the side 48 of the post D, for upwardly bracing the frame B against the post D.

The cable 36 is next unwound from the windlass or drum 35, trained about a pulley hook 49, and at the free end is securely attached to the cable hook 38. The operator then oscillates the lever 40, so that the tooth 41 will engage the teeth 42 and rotate the drum 35 to wind the cable 36 thereon. The pulley hook 49 is placed to engage the clamp E which is attached to the fence F to be stretched and as the lever 40 is oscillated upon the extension of the drum 35 the cable 36 is wound upon the drum 35 so that the fence F will be drawn by means of the clamp E toward the post D, to which the fence is to be attached. The pawl 45 is provided for cooperation with the teeth 42 to maintain the cable taut.

In some instances, it will be desirable to stretch single strands of wire fencing, such as when building a barbed wire fence. To this end a spindle 50 has been provided extending substantially vertically upwardly through one of the cross bars 14 for receiving a roll 51 of single strand fencing. The construction of such fencing can be easily followed in view of the above description.

Various changes in the shape, size, and formation of parts may be made in the form of the invention herein shown and described, without departing from the spirit of the invention or the scope of the claims.

I claim:

1. A wire stretching device, comprising in combination a frame, a transporting wheel mounted within said frame, ground engaging means on said frame, a brace rod pivotally and slidably mounted on said frame for cooperation with said ground engaging means to brace the wire stretcher, and wire stretching apparatus on said frame. 100

2. A wire stretcher, comprising in combination an elongated polygonal shaped frame, a wheel mounted within said frame adjacent one end thereof, ground engaging means adjacent the other end of said frame, and a brace rod slidably and pivotally mounted on said frame adjacent said transporting wheel for cooperation with said ground engaging means to brace the wire stretcher. 110

3. A wire stretching device comprising a supporting frame, a supporting wheel carried at the front end of said frame arranged in a plane centrally of said frame, a rod at the opposite end of said frame having a drum rotatably supported thereby, a cable carried by said drum, hooks carried by said rod upon each side of the drum thereon, a rod transversely carried by said frame intermediate the ends of the latter, and a brace bar pivoted to said last mentioned rod for swinging in a vertical plane and for adjustment by sliding transversely on said rod. 120 125

GRANT SMITH.
